UNITED STATES PATENT OFFICE.

CHARLES C. JESSEN, OF WILMINGTON, DELAWARE, ASSIGNEE TO ATLAS POWDER COMPANY, OF WILMINGTON, DELAWARE, A CORPORATION OF DELAWARE.

METHOD OF MANUFACTURE OF ARTIFICIAL SILK.

Application filed March 20, 1925. Serial No. 17,133.

This invention relates to a step in the manufacture of artificial silk and it has for its object to provide means for imparting uniform tension to the silk during its manufacture with the result that a greatly improved product is secured.

In the manufacture of artificial silk by the copper ammonium process, using what is known as the wet twist or pot twisting method, a plurality of strands from the spinnerets are passed, in parallelism, through a centrally disposed guide tube to the interior of a rapidly whirling pot or centrifuge and the several strands are twisted 10 into a thread by the action of this pot in carrying the thread around the axis constituted by the guide tube. This is the common and well known practice and forms no part of the present invention. The thread 15 builds up on the inside of the centrifuge in the form of a "cake" and when a sufficient amount has been collected in the centrifuge it is removed, still in the form of a cake and the thread is withdrawn from said cake and 20 wound upon a rotating cylinder or bobbin, which may or may not run in a decopperizing bath. The thread is thereafter dried while still mounted upon the cylinder or 25 bobbin. More tension is imparted to the silk during the beginning of the spinning 30 operation in the centrifuge than toward the end thereof, or at the time when the pot has been sufficiently filled and the cake is to be 35 removed. This arises from the fact that the centrifugal force is greater when the pot is empty and such centrifugal force is exerted the entire distance between the guide tube 40 and the wall of the centrifuge, than is the case when the internal diameter of the cake has been materially reduced by the building 45 up of said cake.

It is the primary object of the present invention to compensate for this difference in tension exerted by the difference in centrifugal force at different periods of the filling of the centrifuge, by thereafter winding and drying the threads upon a cylinder or bobbin of such determinate size with respect to the size of the centrifuge as to exert 50 a compensating tension upon the threads. In the accompanying drawing, Fig. 1 is a view partly in section and partly in side elevation of one of the bobbins hereinafter described and Fig. 2 is a sectional view of

one of the centrifuge pots. In the drawing, 5 designates one of the centrifuge pots, which is, under the usual practice, rotated at a high rate of speed during the time that a plurality of threads in parallelism are being fed through the guide tube 5^a. The threads are twisted into a unitary strand about the axis of the tube 5^a by the whirling action of the centrifuge pot. It is manifest that when the cake of the thread 60 begins to build up in the pot, as indicated in Fig. 2, the tension upon the reach of the threads extending between the lower end of the tube and the side of the pot, is greatest and that this tension or strength 65 gradually decreases as the cake builds up toward the center of the pot. After the cake has been built up to the desired size, it is removed from the pot and the thread is 70 withdrawn from the outside of the cake, 75 passed over any suitable guide, such as a hook 7, and is wound upon a spool or bobbin 8, under the influence of a traverse arm 9. The means for rotating the bobbin and for actuating the traverse arm form no 80 part of the present invention. It is common practice to wind thread upon a bobbin directly from the cake and over a suitable guide means, such a structure being illustrated in my co-pending application, Serial 85 Number 749,093, filed on the 10th day of November, 1924.

As before stated, thread that is to be wound on the bobbin is withdrawn from the outside of the cake. As the cylinder or bobbin 90 becomes filled, it will, in effect, have an increased diameter. Thus, that part of the thread which is the first to enter the centrifuge or pot and which has the greatest stress 95 imparted thereto, by centrifugal force, will be the part that will be wound upon the cylinder at the beginning of the winding operation. As the thread builds up upon the cylinder the effective diameter of the cylinder is increased and the speed of travel of the thread over guide 7 and consequently the pull upon the thread, by said guide, is likewise increased. Thus the thread that was the last to enter the centrifuge and 100 which consequently received the least stress will be the part that will receive the most stress in being wound upon the cylinder. Thus, in the winding upon the cylinder or bobbin, I compensate for inequalities of ten- 105

sion occurring during the winding in the centrifuge pot and produce a thread having a uniform tension or stretch at all points in its length. The foregoing results are achieved by having the cylinder or bobbin and the centrifuge pot in proper proportions with relation to each other. One proportion which I have found to give the desired results, is as follows. Where the outside diameter of the cake is four and one-half inches. I use a bobbin of three and one-half inches in diameter and of such length as to produce about the same length of thread traverse on the bobbin as was traversed in making the cake. The result of this is to build the thread on the bobbin in such form that its finished diameter is about the diameter of the outside of the cake.

Since the cylinder or bobbin and the centrifuge pot are in determinate proportions to each other it follows that when the thread is dried on the cylinder or bobbin, that part of the thread which receives the most stress in the twisting pot receives the least or none at all, during the drying process on the cylinder and that the threads receiving the least or minimum stress in the pot receive the maximum stretch or strain during such drying period. In other words, a secondary, compensatory stretching action takes place during the drying period, that is in addition to the compensating action that takes place during the winding upon the bobbin. This is due to the fact that after the thread is washed while wound on the bobbin, as is the common practice, it is in a more or less swollen condition. In other words, the thread is more swollen when wet than when in the acid condition. This swelling of the wet thread has the effect of further stretching the outer layers of thread on the bobbin. The drying takes place from the outside and dries the thread under tension, which tension decreases as the bobbin of thread dries on down to the bobbin itself.

The net result of the whole operation is that stretches or strains in the individual fibers or filaments are equalized throughout the complete length of the threads, so made. This is of a very great importance because it results in producing a thread that is of a uniform hardness and strength so that when it is woven into an artificial silk cloth all parts of the cloth will absorb dye to the same extent and thus produce an absolutely uniform color. The production of a uni-

form color in dyeing of goods of this sort is not possible when one part of the cloth is of a different texture from another.

Having described my invention what I claim is:

1. The herein described step in the manufacture of artificial silk which consists of winding the thread in a centrifuge into a cake and then winding all of the thread of a cake upon a cylinder and from the outside of said cake, said cylinder being of such proportion, with respect to the diameter of the cake, that as the thread is wound upon the cylinder those portions of the thread which were subjected to the greatest tension, by centrifugal force in the centrifuge, will be subjected to the least tension during such winding and those portions of the thread which were subjected to the least tension in the centrifuge will be subjected to the greatest tension during winding. 75

2. That step in the production of artificial silk which consists of the employment of a centrifuge pot of such proportion with respect to the winding cylinder or bobbin as to produce a uniform tension upon the finished product when the thread is wound upon said bobbin from the outside of the cake produced in the centrifuge pot. 80

3. That step in the manufacture of artificial silk which consists of winding the thread from the outside of a cake produced in a centrifuge pot, over a guide and upon a bobbin of such diameter, with respect to the centrifuge pot, as to equalize the non-uniform stretch imparted to the thread in the centrifuge pot. 90

4. The herein described step in the manufacture of artificial silk which consists of winding the thread in a centrifuge into a cake and then winding all of the thread of a cake upon a cylinder and from the outside of said cake, said cylinder being of such proportion, with respect to the diameter of the cake, that when the thread is dried upon the cylinder those portions of the thread which were subjected to the greatest tension, by centrifugal force in the centrifuge, will be subjected to the least tension during such drying and those portions of the thread which were subjected to the least tension in the centrifuge will be subjected to the greatest tension during drying. 100

In testimony whereof he affixes his signature. 110

CHARLES C. JESSEN.
